UNITED STATES PATENT OFFICE.

FRANCIS A. WINSLOW, OF CHICAGO, ILLINOIS.

DESIGN FOR LATTICE OR MESH WORK.

SPECIFICATION forming part of Design No. 19,145, dated June 4, 1889.

Application filed May 9, 1889. Serial No. 310,147. Term of patent 7 years.

To all whom it may concern:

Be it known that I, FRANCIS A. WINSLOW, a citizen of the United States, residing at Chicago, in the county of Cook and State of Illinois, have invented and produced a new and original Design for Lattice or Mesh Work, of which the following is a specification, reference being had to the accompanying drawing, forming part hereof, which is a face view of my newly-designed lattice-work.

The leading feature of my design consists in a series of parallel bars and intermediate diagonal bars and of a series of parallel bars at right angles to the first bars, and intermediate diagonal bars that cross the diagonal bars of the first series.

In the drawing, the letters A represent a

series of parallel bars, some of which are in different planes, and B represents intermediate diagonal bars between two bars A. D ²⁰ represents parallel bars in different planes at right angles to the bars A, and E represents diagonal bars between two bars D. The bars E cross the bars B, as shown.

I claim—

The design for a lattice-work herein shown, consisting of the parallel bars A and diagonal intermediate bars B, and of the parallel bars D and intermediate diagonal bars E, that cross the bars B, substantially as shown.

FRANCIS A. WINSLOW.
